UNITED STATES PATENT OFFICE.

JACOB A. HAMELBACK, OF ZANESVILLE, OHIO.

VEHICLE.

SPECIFICATION forming part of Letters Patent No. 662,267, dated November 20, 1900.

Application filed April 30, 1900. Serial No. 14,995. (No model.)

To all whom it may concern:

Be it known that I, JACOB A. HAMELBACK, a citizen of the United States, residing at Zanesville, in the county of Muskingum, 5 State of Ohio, have invented certain new and useful Improvements in Vehicles; and I do hereby declare the following to be a full, clear, and exact description of the invention, such as will enable others skilled in the art to which 10 it appertains to make and use the same.

One object of my invention is to provide a vehicle which may be propelled by hand-power, foot-power, or both; and a further object is to provide a device of this nature which 15 shall be simple of construction, easy of manipulation, and cheap of manufacture. It is also my object to provide a vehicle which may be propelled by one or more persons, as the case may be. With these objects in view 20 I construct a device of this nature such as is shown in the accompanying drawings and described in this specification, in which like characters of reference indicate similar parts in both views, and in which—

25 Figure 1 is a perspective view of my invention, and Fig. 2 is a side plan view thereof with a part of the floor removed.

By referring to the drawings it will be seen that in order to accomplish the objects named 30 above I provide a rectangular frame *a*, comprising side members *b* and *c* and end members *d* and *e*. The frame is floored, as shown at *f*, and extending forwardly of the frame at one of its ends is a support *g*, in which is 35 journaled a steering-wheel *h*, mounted between the jaws *h'* of a spindle *j*, which extends through the support. Wheels *i* and *k* are mounted at the end of the frame *a* on an axle *l*, journaled therein and extending trans- 40 versely thereof.

Mounted at the forward portion of the frame *a* is a framework *m* to support a vertical spindle *n*, having at its upper end a beveled gear *o*, adapted to mesh with a similar beveled 45 gear *p*, mounted upon a shaft *q*, which extends across the upper end of the framework *m*, parallel with the floor of the frame *a*. Upon the ends of this shaft are mounted cranks *r*, through the medium of which the 50 said shaft may be rotated to give revolution to the bevel-gear *p* and in turn to the bevel-

gear *o*, with its vertical spindle *n*. Upon the lower end of the spindle *n* is mounted a worm-wheel *s*, which meshes with a worm-screw *t*, which is mounted on a shaft *u*, extending 55 transversely of the frame *a*. Upon this shaft *u* is mounted a gear *v*, adapted to mesh with a gear *w*. The gear *w* is carried by a shaft *x*, also carrying a sprocket-wheel *y*, which is connected by means of suitable chains with 60 a sprocket-wheel *z*, mounted upon the shaft *l*, and from the foregoing description it will be seen that as the cranks *r* are revolved motion will be given to the rear wheels of the vehicle through the medium of the train of gears just 65 described.

Mounted upon the end of the spindle *j* is a cross-bar *j'*, to each end of which is loosely secured a rearwardly-extending rod *l*, each of which passes through a pair of guideways 70 2. Pivoted to the free-ends of the rods *l* are levers *3*, which are in turn pivoted between ears *4* and provided with foot-pieces *5*.

Formed upon the rearwardly-extending rods are lugs *6*, each to receive one end of a 75 helical spring *7*, mounted upon and encircling each rod, the opposite ends of the springs having bearings against the innermost guideways. From this it will be seen that each spring bears at one end against a 80 lug and at the other against a guideway, thus holding the bar *j'* normally transversely of the frame and the wheel *h* normally longitudinally thereof.

Secured to the floor of the framework and 85 a little to the rear of the cranks *r* is a seat *9*, to be occupied by an operator of the vehicle should it be operated by but one person, and in this event the vehicle is steered through the medium of the levers *3*, which when operated 90 will turn the steering-wheel either in one direction or the other.

If it is desired that more than one person operate the vehicle, a seat will not be utilized, but instead a number of persons will revolve 95 the cranks *r* in a standing position. The steering mechanism just described will also be dispensed with, and instead a steering-rod 10 may be secured to the upper end of the spindle *j*, to be operated by one of the parties on 100 the floor of the vehicle.

It will be readily understood that I may

make any slight alterations in my invention just described without departing from the spirit thereof.

Having thus described my invention, what I claim is—

1. A device of the class described, comprising a framework, wheels supporting the framework, a supplemental framework mounted vertically of the first-named framework, a spindle mounted in the supplemental framework, means for revolving the spindle, a worm-wheel, mounted upon the spindle in engagement with a worm, a shaft mounted transversely of the framework and carrying the worm, a gear-wheel mounted upon the shaft adjacent the worm, a second gear-wheel engaging with this gear-wheel, a second shaft mounted parallel with the first-named shaft to support the second-named gear, a sprocket-wheel mounted upon the second shaft, a second sprocket-wheel mounted upon the axle of two of the wheels supporting the framework, a chain connecting the two sprocket-wheels, and means for controlling the direction of the vehicle.
2. A device of the class described comprising a framework, a steering-wheel mounted at one end of the framework, a pair of supporting-wheels mounted at the opposite end of the framework, a supplemental framework mounted vertically on the first-named framework, a vertical spindle mounted in the supplemental framework, a beveled gear secured to the upper end of the vertical spin-

dle, a shaft mounted in the supplemental framework at right angles to the vertical spindle, cranks mounted upon the latter for revolving it, a beveled gear mounted upon the shaft in engagement with the beveled gear on the spindle, a worm-wheel mounted upon the lower end of the vertical spindle, a shaft mounted rearwardly of the worm-wheel, a worm mounted upon the shaft and in engagement with the worm-wheel, a gear mounted adjacent the worm, a second gear mounted upon a second shaft extending transversely of the framework said second gear being engaged with the first-named gear, a sprocket-wheel mounted upon the second-named shaft, a sprocket-wheel mounted upon the axle of the rear supporting-wheels and receiving motion from the first-named sprocket-wheel, a spindle extending upwardly from the steering-wheel, a cross-head mounted upon the upper end of the spindle, rods extending rearwardly from each end of the cross-head, levers secured to the ends of the rods, through the medium of which the cross-head may be oscillated and springs mounted upon the rearwardly-extending rods for holding the steering-wheel in a normally fixed position.

In testimony whereof I affix my hand and seal in the presence of two witnesses.

JACOB A. HAMELBACK. [L. S.]
